United States Patent Office

Des. 187,529
Patented Mar. 29, 1960

187,529

BUILDING BLOCK

Reabelle D. Braverman, Cincinnati, Ohio

Application October 9, 1959, Serial No. 57,869

Term of patent 14 years

(Cl. D18—2)

Fig. 1

Fig. 2

Fig. 3

I claim:

The ornamental design for a building block, substantially as shown.
